The schedule referred to in these Letters Patent and making part of the same

To all whom it may concern;

Be it known that J. N. Gibbs of Albany in
the County of Albany & State of New York have invented or produced a new design for cooking
stoves and do hereby declare that the following is a full & exact description of the same.

The design consists of a combination of ornaments with mouldings as particularly repre-
sented in the accompanying drawings to which I make the following references.

Fig 1 represents a lateral elevation of the stove

Fig 2 " front " " "

a " the moulding of the hearth plate

b " the moulding of the doors

c " the ornament of the fire box door

d " the ornament of the oven door

e " the ornament of the side plate

f " the ornament of the front doors

What I claim as my invention and desire to secure by Letters Patent is the
design and configuration of the ornaments and mouldings herein described constituting
